LACE FABRIC

Edgar F. Stiner, New York, N. Y.

Application October 16, 1931, Serial No. 569,204

1 Claim. (Cl. 96—24)

The object of the present invention is to provide a new lace fabric which may be defined as a Swiss and square ground lace employing a warp, and embodying five threads, to wit, warp, spool, 5 Swiss, square ground and bobbin threads. The new lace fabric is an improvement upon the ordinary square ground lace fabric and Swiss lace fabric customarily manufactured on Nottingham lace curtain machines, inasmuch as the new 10 fabric embodies two fillings and in addition, a square ground net.

The invention will be described with reference to the accompanying drawing in which

Fig. 1 is a diagrammatic view showing the 15 guide bars, threads and a bobbin with its carriage together with a jacquard controlling interceptor.

Fig. 2 is a schematic plan view showing an embodiment of the new fabric.

Fig. 3 is a schematic plan view showing the possible traverses of the spool thread.

Fig. 4 is a schematic plan view showing the traverses of the square ground thread.

By reference to Fig. 1, it will be seen that in the manufacture of the new fabric on a jacquard 25 control Nottingham lace machine, an additional thread guide bar is introduced, the machine embodying four bars, to wit, a spool bar 19, a Swiss bar 20, a beam bar 21 and a warp bar 22. A jacquard control interceptor 23 is employed for

30 each spool thread *a* and its companion Swiss thread *b*. At 24 I have shown one of the bobbins in its carriage 25, the bobbin thread being indicated at *c*. The lace is indicated at 26 and the horizontal line of lace formation at 27.

35 In the application of my novel fabric, the square ground thread in its traverse crosses two wales so that the horizontal square ground ties will be doubled. The traverse of the Swiss thread bar is arranged the reverse of the traverse of

40 the spool thread bar. In other words, the ties of the Swiss thread are made by interception and the Swiss threads pillar when not intercepted.

To illustrate this, reference to Fig. 1 will show the interceptor 23 in engagement with the spool 45 thread but not intercepting the Swiss thread.

In view of the reverse traverse of the spool and thread bars 19 and 20, this position of the elements will cause the spool thread to pillar with the warp and the Swiss thread to pillar with 50 the warp. When the interceptor releases the spool thread, the latter will make a three gait tie. The beam or square ground threads are not intercepted and therefore are uniformly tied with the warp to form a square net. As stated 55 above, the traverse of the square ground threads

in the present fabric is three gaits so that the horizontal square ground ties will be double.

In Fig. 2 I have shown the square ground threads merely by horizontal lines in order that the laying of the Swiss and spool threads may 60 be more clearly illustrated. I have also omitted the bobbin threads for the same reason. The bobbin threads, as customary, will tie the spool, Swiss and beam threads to the warp.

By referring to Fig. 2, it will be noted that 65 the warp threads are shown at 1, 4, 7, 10, 13, and 16. Two sets of filling threads are shown comprising, namely; Swiss threads and the spool threads. To better illustrate the position of these threads, I have shown the spool threads 70 in full lines and the Swiss threads in dotted lines.

In Fig. 2 the first spool thread is shown at 2. The interceptors at both sides of that thread being in, the thread pillars until it reaches the second horizontal line formed by the beam threads, 75 and at that point, one interceptor being out, the thread traverses to the right, back to the left, to the right again, and thence to the left. At the last named point, both interceptors are in, and the thread pillars to the bottom of the lace section shown in the sketch. In Fig. 2, the Swiss thread is shown at 3 in dotted lines. The interceptors being out, the Swiss thread pillars until it reaches the third line of horizontal beam threads. At such point, one interceptor is in, 85 and one out, so that the Swiss thread is traversed to the right, thence to the left, thence to the right, thence to the left, and from such point pillars downward without further traverse.

Referring again to Fig. 2, the spool thread 6 pil- 90 lars until it reaches the first line of horizontal beam threads shown in the sketch, one interceptor being out and one in, the thread is traversed to the right, thence to the left, thence to the right, thence to the left; both interceptors being in, 95 the thread pillars until it reaches the first point of tie at which point one interceptor is out, whereupon the spool thread traverses to the left, thence to the right, thence to the left, thence to the right, from which point it pillars without fur-

ther traverse. The Swiss thread 5 pillars to the third horizontal line of beam threads because of the interceptors are set out. At that point, one interceptor being in and one out, the thread trav- 100 erses to the right, whereupon, both interceptors being in, the thread traverses across warp thread 4 to warp thread 1, thence back across warp thread 4 to warp thread 7, thence to the left across warp thread 4 to warp thread 1, thence

105 being in, the thread traverses across warp thread 4 to warp thread 1, thence back across warp thread 4 to warp thread 7, thence to the left across warp thread 4 to warp thread 1, thence 110 back across warp thread 4 to warp thread 7.

At this point, one interceptor is out so that the said Swiss thread is traversed to the left to warp thread 4, thence to the right back to warp thread 7, thence to the left to its original position adjacent warp thread 4. At the last named point, the interceptors move out and as both interceptors are out, Swiss thread 5 pillars.

Referring again to Fig. 2, the third spool thread is shown at 8. Both the interceptors are in, the 10 spool thread pillars on warp thread 7 until it reaches the first horizontal beam threads, the latter acting with the warp to form the net. At this point, one interceptor being out, the said spool thread 8 traverses to the right to warp 15 thread 10, whereupon both interceptors being out, spool thread 8 is traversed to warp thread 4, thence across warp thread 7 to warp thread 10, thence back to the left across the warp thread 20 7 to warp thread 4, whereupon one interceptor being in, spool thread 8 is traversed to the right at which point both interceptors are in and the said spool thread 8 pillars to the third horizontal line of beam threads. At this point, one interceptor is moved out and the other remaining, the 25 spool thread 8 is traversed to the right to warp 10, thence back to warp 7, thence to the right to warp 10, thence to the left from which point it pillars. Associated with warp thread 7 is Swiss 30 thread 9. That thread pillars to a point below the third line of horizontal beam threads whereupon one interceptor being out, Swiss thread 9 is traversed to the left to warp thread 4, thence to the right back to warp thread 7, thence to the left to warp thread 4. At the last named 35 point, both interceptors being in, Swiss thread 9 traverses to the right across warp thread 7 to warp thread 10, thence to the left across warp thread 7 to warp thread 4, thence to the right back to warp thread 10 at which point one interceptor being out and one in, the Swiss thread 40 9 is traversed to its original relation with warp thread 7 and pillars on the warp thread.

The fourth spool thread is shown in Fig. 2 at 11, where it pillars along warp thread 10 to the first horizontal net threads. One interceptor being out, spool thread 11 is traversed to warp 45 13, whereupon both interceptors being out, spool thread 11 is traversed across warp thread 10 to warp thread 7, thence back to warp thread 13, thence back to warp thread 7, thence to the right back to warp thread 13. At the last named point, one interceptor being in and the other out, spool 50 thread 11 is traversed to the left and to warp thread 10, thence to the right to warp thread 13, thence back to warp thread 10. Both interceptors being in, spool thread 11 pillars a short 55 distance whereupon with one interceptor out, spool thread 11 is traversed to the left to warp thread 7, thence to the right back to warp thread 10, thence back to warp thread 10. At this point, both interceptors are in and spool thread 11 pillars. The Swiss thread 12 associated with warp thread 60 10 pillars to a point below the third set of horizontal threads of the net at which point one interceptor being in, Swiss thread 12 is traversed from warp thread 10 to warp thread 13, thence back to warp thread 10, thence to the right to warp thread 13. At this point, both interceptors 65 are in and Swiss thread 12 is traversed across warp thread 10 to warp thread 7. At this point, one interceptor is in and the other out so that Swiss thread 12 traverses to the right and to warp 70 thread 10, thence to the left to warp thread 7, thence to the right to warp thread 10, thence 75

to the left to warp thread 7, and thence back to the right to warp thread 10. Both interceptors being out, the Swiss thread pillars from the last named position.

The fifth spool thread shown in Fig. 2 and indicated at 15 pillars to a point below the first set of horizontal beam threads at which point one interceptor being in, spool thread 15 is traversed to the left to warp thread 10, thence back to warp thread 13 and thence to the left to warp thread 10. At this point two interceptors being out, spool thread 15 is traversed to the right across warp thread 13 and to warp thread 16, thence to the left and to warp thread 10, thence to the right to warp thread 16, thence to the left to warp thread 10, thence back to warp thread 16. At this point, one interceptor being in and one out, the said spool thread 15 is traversed back to its initial position relatively to warp 80 thread 13, thence to the right to warp thread 16, thence to the left to warp thread 13. At the last named point, both interceptors being in, spool thread 15 pillars. The Swiss thread 14 associated with warp thread 13 pillars to a point 85 below the third set of horizontal beam threads. At this point one of the interceptors being in, Swiss thread 14 crosses to the left to warp thread 10, thence to the right to warp thread 13, thence to the left to warp thread 10, thence to the right to warp thread 13, thence to the left to warp 90 thread 10, and thence back to warp thread 13 at which point it pillars. 95

The sixth spool thread is indicated in Fig. 2 at 17, and it pillars to a point below the second set of horizontal beam threads. At that point, 100 one interceptor being out, spool thread 17 is traversed to the left and to warp thread 13, thence to the right to warp thread 16, thence to the left to warp thread 13, again to the right to warp thread 16, thence to the left to warp thread 13, then to the right to warp thread 16, from 105 which point it is traversed to the left and to warp thread 13, thence back to warp thread 16, at which point it pillars. The Swiss thread 18 associated with warp 17 pillars from top to bottom 110 of the lace formation shown in the drawing. 115

To further illustrate the action of the spool three-gait traverse under control of the interceptors, reference to Fig. 3 will show the possible traverses. To the point 28 the spool thread *a* has 120 pillars, both interceptors being in. By both interceptors is meant the interceptors at each side of the thread. At point 28 the two interceptors are out and the spool thread is traversed to the right hand warp and thence across the middle 130 warp to the left hand warp, the traverse movements continue until said spool thread reaches the point 29. At such point, both interceptors are in and the spool thread pillars until it reaches the point 30. At that point one interceptor, 135 which may be termed the interceptor at the left of the thread, is in, so that the thread traverses to the right hand warp and thence to the middle warp, this action continuing to the point 31. At this point, both interceptors being in, the said 140 spool thread pillars to the point 32. At such point, the interceptor to the left is out but the interceptor to the right is in, therefore, the spool thread must traverse to the left, thence back to the center warp thread, thus continuing to the point 33, at which point both interceptors being in, the spool 145 thread pillars. 140

Inasmuch as the Swiss thread bar has a traverse opposite that of the spool thread bar, the action 150

of the interceptors will be the reverse of those for the spool thread.

The diagrammatic view, Fig. 4, illustrates the traverse of the beam bar thread, or square ground thread, the beam bar making its cycle in four complete motions. From the point 34 to the point 35 the beam thread traverses to the left three gaits, remains adjacent the left hand warp to the point 36 from which point it traverses to the right one gait and to 37, thence to the left one gait to point 38. From this point it traverses to the right three gaits, thence to the left one gait to the point 39, thence to the right one gait to the point 40, where it remains in position to the point 41 for repeat.

The embodiment illustrated in Fig. 2 is merely one of many Swiss and spool thread arrangements possible under the invention as will be understood by those skilled in the art and upon reference to possible three-gait traverse of either of the threads. The characteristic of the invention,

therefore, is a lace fabric embodying a square net formed by warp and square ground threads and filling comprising laterally traversed and pillared Swiss and spool threads, the three last named threads being tied to the warp by the usual bobbin threads. By employing Swiss and spool threads of contrasting shades or colors, as, for example, ecru and light brown, old patterns of hand made square ground lace may be closely simulated by reason of the construction, the lace being strong and durable.

Having described my invention, what I claim and desire to secure by Letters Patent, is as follows:

A lace fabric comprising a warp, square ground threads laid in double horizontal ties, spool and Swiss threads employed as fillings, the spool and Swiss threads being independently and reversely traversed, and bobbin threads tying the spool, Swiss and square ground threads to the warp.

EDGAR F. STINER.
